UNITED STATES PATENT OFFICE

145,027

DESIGN FOR A DISPLAY CABINET OR SIMILAR ARTICLE

Stephen Kassovic, La Salle, Ill.

Application November 7, 1945, Serial No. 123,531

Term of patent 14 years

(Cl. D80—11)

To all whom it may concern:

Be it known that I, Stephen Kassovic, a citizen of Czechoslovakia, residing at La Salle, in the county of La Salle and State of Illinois, have invented a new, original, and ornamental Design for a Display Cabinet, or Similar Article, of which the following is a specification, reference being had to the accompanying drawing, forming part thereof.

Figure 1 is a perspective view of a display cabinet, or similar article, showing my new design, Figure 2 is a top plan view, and Figure 3 is a bottom plan view thereof.

I claim:

The ornamental design for a display cabinet or similar article, as shown.

STEPHEN KASSOVIC.
